DESIGN FOR AN ELECTRIC GEAR SHIFT MOTOR

Homer E. Reeder, Lima, Ohio

Application April 6, 1939, Serial No. 84,094

Term of patent 7 years

To all whom it may concern:

Be it known that I, Homer E. Reeder, a citizen of the United States, residing at Lima, in the county of Allen and State of Ohio, have invented a new, original, and ornamental Design for an Electric Gear Shift Motor, of which the following is a specification, reference being had to the accompanying drawing, forming part thereof.

Figure 1 is a view in perspective looking at one side of an electric gear shift motor embodying the design;

Figure 2 is a view in perspective looking at the opposite side of the motor.

Figure 3 is a view in elevation of the outer end of the motor.

I claim:

The ornamental design for an electric gear shift motor, as shown.

HOMER E. REEDER.
